UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

ELASTIC-FLUID TURBINE.

1,255,650.

Specification of Letters Patent. Patented Feb. 5, 1918.

Application filed March 25, 1916. Serial No. 87,166.

To all whom it may concern:

Be it known that I, FREDERICK SAMUELSON, a subject of the King of Sweden, residing at Rugby, county of Warwickshire, England, have invented certain new and useful Improvements in Elastic-Fluid Turbines, of which the following is a specification.

The present invention relates to elastic-fluid turbines and has for its object to reduce or eliminate the losses caused by erosion of the blades.

It is well known that the presence of water in steam passing through the blading elements of a steam turbine causes erosion of the inlet edges of the blades. The effect of this erosion is to increase the shock losses of the steam at the entrance to the blades whereby the efficiency is reduced with a consequent increase in the steam consumption of the turbine per unit output.

My invention comprises providing in all or any of the rows of blading subject to erosion, one or more blades whose entrance edge is nearer to the preceding nozzle or row of blades than the rest of the blades.

The effect of this projecting inlet edge of the blade or blades is to receive the shock of and disintegrate into very finely divided particles the water carried in suspension by the steam. Wet steam passing through a nozzle deposits a considerable quantity of the moisture on the surface of the nozzle and this water gradually accumulates as it travels comparatively slowly along the walls of the nozzle to the exit thereof. The water deposited by the steam creeps along the nozzle surface until the extreme edge is reached and the drop or globule remains clinging to the surface until the force of the steam acting on its mass is greater than the oppositely acting force of surface tension. Eventually the drop of water is released from the nozzle surface and travels toward the blading on the turbine wheel. It takes a certain time for the water globule to travel the distance between the lip of the nozzle and the passing blade edges, and, therefore, the number of protective blades, or blades with projecting entrance edges, will bear relation to the diameter and number of revolutions which the turbine wheel is making and the amount of clearance provided between the nozzle and the blades.

It has been found from experiment that in a turbine wheel provided with two pro-

jecting blades such as described above, these projecting blades were more corroded than the remaining blades.

The invention, therefore, provides a means for concentrating the erosion on a small proportion of the total number of blades. Since the projecting blades will get all or nearly all of the erosion it is desirable that they should be made or fitted in such a manner that they can be easily replaced or that they should be made of material such as will successfully resist erosion.

The projecting blades may also be constructed with a renewable entrance edge of a specially hard erosion resisting metal. This renewal edge may be fixed to the rest of the bucket by a dovetail or any other approved method so that it can be readily removed for renewal purposes.

In the accompanying drawing, Figure 1 shows a radial section through the rim of the turbine wheel with the blades mounted thereon; Fig. 2 is a developed end view of a portion of a turbine wheel; Fig. 3 is an enlarged view of a single blade illustrating a form of my invention, and Fig. 4 is a side elevation of a turbine wheel embodying my invention.

Referring to the drawing, 5 indicates the web of a turbine wheel and 6 turbine blades mounted thereon. 7 indicates the edge portion of a blade which projects beyond the edges of the remaining blades. In Fig. 2 two of the blades 6 are shown as being provided with the projecting edge portion 7 as already described. This projecting edge portion 7 may be formed integral with the bucket, in which case the bucket may be made of special erosion resisting material, or it may be formed of a separate piece as shown in Fig. 3, wherein 8 indicates the main portion of the bucket and 9 the projecting edge portion. In this case the projecting portion 9 only will preferably be made of special erosion resisting material, although the whole bucket may be. By the arrangement shown in Fig. 3 it will be clear that the portion 9 can be readily renewed since it is connected to portion 8 by a dovetail as indicated at 10. In Fig. 4 the wheel is shown as being provided with four buckets having projecting edges, such buckets being indicated at 11.

In accordance with the provisions of the patent statutes, I have described the prin- 110

ple of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

- 10 1. In an elastic fluid turbine, the combination of a wheel and working blades mounted thereon, the entrance edge of at least one working blade, but not more than several such blades spaced substantial distances apart, having its entrance edge projecting nearer to the preceding nozzle or row of blades than the other working blades, the number of working blades having such projecting edges depending on the peripheral speed of the wheel and the clearance between the entrance edges of the blades which do not have projecting edges and the preceding nozzle or row of blades.
- 20 2. The combination in an elastic-fluid turbine, of a bucket wheel having a blade, the entrance edge of which projects nearer to the preceding nozzle or row of blades than the next adjacent blades, such blade being formed of a metal which offers a greater resistance to erosion than the metal of the other blades.
- 30 3. The combination in an elastic-fluid turbine, of a bucket wheel having a blade, the entrance edge of which projects nearer to the preceding nozzle or row of blades than the next adjacent blades, the entrance edge of such blade being formed of a metal which offers a greater resistance to erosion than the metal of the other blades.
- 40 4. The combination in an elastic-fluid tur-

bine, of a bucket wheel having a blade, the entrance edge of which projects nearer to the preceding nozzle or row of blades than the next adjacent blades, the entrance edge of such blade being formed separate from and detachably connected to the other portion of the blade.

5. The combination in an elastic-fluid turbine, of a bucket wheel having a blade, the entrance edge of which projects nearer to the preceding nozzle or row of blades than the next adjacent blades, the entrance edge of such blade being formed separate from and detachably connected to the other portion of the blade, and made of erosion resisting metal.

6. The combination in an elastic-fluid turbine, of a bucket wheel having blades at spaced points around it, the entrance edges of which project nearer to the preceding nozzle or row of blades than the others, the entrance edges of such blades being detachably connected to the other portions of said blades.

7. The combination in an elastic-fluid turbine, of a bucket wheel having blades at spaced points around it, the entrance edges of which project nearer to the preceding nozzles or row of blades than the others, the entrance edges of such blades being detachably connected to the other portions of said blades and formed of erosion resisting metal.

In witness whereof, I have hereunto set my hand this seventh day of March, 1916.

FREDERICK SAMUELSON.

Witnesses:

CHARLES H. FULLER,
J. A. FOSTER.

It is hereby certified that in Letters Patent No. 1,255,650, granted February 5, 1918, upon the application of Frederick Samuelson, of Rugby, England, for an improvement in "Elastic-Fluid Turbines," an error appears in the printed specification requiring correction as follows: Page 2, line 69, claim 7, for the word "nozzles" read *nozzle*; and that the said Letters Patent should be read with this correction therein that the same may conform to the record of the case in the Patent Office.

Signed and sealed this 19th day of March, A. D., 1918.

[SEAL.]

R. F. WHITHEAD,

Acting Commissioner of Patents.
